UNITED STATES PATENT OFFICE.

ERNEST BEATY, OF CENTRAL CITY, NEBRASKA.

DESIGN FOR A COMBINED DISPLAY AND SIGN BOARD.

Application filed June 5, 1924. Serial No. 9,803. Term of patent 3½ years.

To all whom it may concern:

Be it known that I, ERNEST BEATY, a citizen of the United States, residing at Central City, in the county of Merrick and State of Nebraska, have invented a new, original, and ornamental Design for a Combined Display and Sign Board, of which the following is a specification, reference being had to the accompanying drawing, forming a part thereof.

Figure 1 is a front elevation showing my new design.

Figure 2 is an end elevation thereof.

I claim:—

The ornamental design for a combined display and sign board, as shown.

ERNEST BEATY.
